UNITED STATES PATENT OFFICE

2,132,163

FOUNDRY SAND CONDITIONING APPARATUS

Fred B. Henry, Columbus, Ohio, assignor to The Jeffrey Manufacturing Company, a corporation of Ohio

Application October 5, 1934, Serial No. 747,042

3 Claims. (CL 22—89)

My invention relates to portable foundry sand conditioning apparatus adapted for use in small foundries or in foundries where complete conditioning plants of the stationary type are not used, and one of the objects of the invention is the provision of improved and efficient apparatus for screening the foreign material from used foundry sand and aerating the screened sand for re-use in foundry work.

Another object of the invention is the provision of improved apparatus for separating certain materials and directing the same to convenient locations for efficient handling.

A further object of the invention is the provision of improved ejector and discharge mechanism combined with means for directing granular material thereto.

Other objects of the invention will appear hereinafter, the novel features and combinations being set forth in the appended claims.

In the accompanying drawings,

Fig. 1 is an elevation of my improved portable foundry sand conditioning apparatus;

Fig. 2 is a plan view of the structure shown in Fig. 1;

Fig. 3 is a rear view of the structure shown in Fig. 1;

Fig. 4 is an enlarged longitudinal sectional elevation of the portable outfit shown in Figs. 1 and 2, taken on the line 4—4 of Fig. 3, looking in the direction of the arrows;

Fig. 5 is a transverse sectional elevation taken on the line 5—5 of Fig. 1, looking in the direction of the arrows;

Fig. 6 is a plan view taken on the line 6—6 of Fig. 5 to show the shape of the flights of the ejector mechanism; and

Fig. 7 is an enlarged sectional elevation of a portion of Fig. 4, taken on the line 7—7, looking in the direction of the arrows.

Referring to Figs. 1 to 4 inclusive, it will be seen that the portable sand conditioning apparatus comprises a vehicle having the main frame 8 mounted on the rear wheels 9, 9 and the front steering wheel 10. The single front wheel 10 is mounted on a frame 11 having a vertical steering post 12 with a reduced portion 13 journaled in the front bearing 14 at the front end of the main frame 8. The protecting canopy 15 may be rigidly connected to the frame 11 and the steering post 12, as shown in Fig. 4. A drawbar 16 pivoted at 17 to the steering post 12 is provided at the front end with a pulling handle 18, as shown in Figs. 1 and 2.

Used foundry sand may contain such foreign

materials as pieces of metal of various shapes and sizes, caked lumps of sand, refuse, etc., and moreover a pile of used foundry sand on the foundry floor may be wet ununiformly at the bottom and therefore not in condition for use until after having been mixed and aerated. When the material from such pile is shoveled into the hopper 19 while the apparatus shown in Fig. 4 is being operated, the foreign material will be transferred continuously to the chute 20, and the usable foundry sand will be directed to the ejector mechanism for aerating and mixing the sand and throwing it along the chute 22 out from the rear end of the machine into a windrow or pile spaced from the machine.

The hopper 19 is mounted on a supplemental frame 23 which in turn is mounted on the main frame 8 so as to be universally tiltable relatively thereto. Preferably, two pairs of spaced-apart springs 24, 24 are mounted on opposite sides of the supplemental frame 23. Each of the springs 24 may be retained in place by means of the structure shown in Fig. 7. An inverted cup-shaped bracket 25 is bolted at 26 to the inner wall of the supplemental frame plate 23 in position for the hollow boss 21 to project into the upper end of the spring 24. A horizontal bracket 8' projects inwardly from one of the sides of the frame 8 in position to receive the lower end of the spring 24. The head 28 of a bolt 29 may be used as a retaining boss for the lower end of the spring 24. The lower edges of the cup-shaped brackets 25 are spaced sufficiently above the bracket plates 8' to permit universal tilting of the supplemental frame 23 relatively to the main frame 8.

Secured to the supplemental frame 23 is a hopper 30 located below the screen 31. In order to reinforce the screen and keep the same from sagging a longitudinal bar 32 may be secured at its ends to the upper ends of the hopper 30 midway between the sides of the screen 31, as shown in Fig. 5.

Welded to the inner side walls of the hopper 19 are abutment plates 33, 33 as shown in Figs. 4 and 5. Longitudinal rods 34, 34 welded to the longitudinal edges of the screen 31 may be located on the horizontal edges 35, 35 of those portions 30', 30' of the hopper 30 which are located at the sides of the supplemental frame 23.

Retaining plates 36, 36 are provided at their lower edges with beveled extensions 37, 37 which are adapted to engage the rods 34, 34. Bolts 38, 38 may be relied on to secure the retaining plates 36 with their upper edges in engagement

with the abutment plates 33 and with their lower beveled extensions 37 in engagement with the rods 34, thereby not only securing the screen 31 in connection with the supplemental frame 5 23 but also holding said screen under lateral tension. The longitudinal central bar 32 co-operates with the lateral edge supports to maintain the screen 31 in a horizontal plane during operation.

10 In order to effect such vibration of the screen 31 as to transfer foreign material or unscreened material rearwardly along the screen 31 to the transverse chute 20, I have provided gyratory vibrating mechanism for the supplemental frame 23.

15 By referring to Figs. 4 and 5, it will be noted that upper bearing blocks 39, 39 and lower bearing blocks 40, 40 are rigidly secured to the main frame 8 at the sides thereof. Journaled by means 20 of the ball bearings 41, 41 in the fixed bearing blocks 39, 39 are the reduced end portions 42, 42 of the transverse shaft 43. At the inner ends of the reduced extensions 42 are eccentrics 44, 44 which are journaled by means of the ball bearings 45, 45 in the ends of the tubular transverse housing 46, the ends of which are rigidly secured to the side walls of the hopper 19 and to the side walls of the supplemental frame 23.

25 At the inner ends of the reduced extensions 42 adjacent to the eccentrics 44 are keyed the fly wheels 47, 47 to rotate with the shaft 43. Weights 30 48, 49 may be detachably connected by means of bolts 50, 51 to either or both of the fly wheels 47 and these weights may be so arranged as to 35 counterbalance the throw or momentum of the supplemental frame and the screen thereon, relatively to the main frame, and thereby lessen the vibration of the main frame 8.

30 Spaced below the transverse shaft 43, as shown in Figs. 4 and 5, is a transverse shaft 52, the ends of which are journaled by means of the ball bearings 53, 53 in the bearing blocks 40, 40.

35 Keyed to the shaft 52 intermediate the ends thereof are two spiders 54, 54 each having a pair 40 of radial arms 55, 56 to the outer ends of which are detachably connected by means of the bolts 57, 58 the flights 59 and 60, as shown in Figs. 5 and 6.

40 Mounted at the upper rear portion of the main frame 8 is an electric motor 61, as shown in Figs. 1 to 4, inclusive. Mounted at the outer end of the armature shaft 62 is a pulley 63 adapted to drive a belt 64 which is in engagement with the V-shaped grooves 65' and 66' of the pulleys 65 45 and 66 which are respectively secured to the shafts 43 and 52, as shown in Fig. 5. The pulleys 63, 65 and 66 may be protected by the covering casings 67 and 68. The fly wheels 47, 47 may be provided with the canopies 69, 69.

45 60 Lubricating connections for the ball bearings 45, 45 may be provided as indicated at 70, 70. Likewise, lubricating connections may be provided for the ball bearings 41, 41 as indicated at 71, 71. Provision may be made for lubricating the ball bearings 53, 53 as indicated at 72, 72. The shafts 43 and 52 may be held against end-wise movement as indicated at 73, 73 and 74, 74.

70 75 The armature shaft 62 must be rotated in a clockwise direction as viewed in Fig. 4, so that the belt 64 will travel in the direction of the arrows 75, because the shafts 43 and 52 must rotate in clockwise directions, as viewed in Fig. 4. This is for the reason that the eccentrics 44 must produce a gyratory movement of the supplemental frame in a clockwise direction, as viewed

in Fig. 4, thereby transferring unscreened material or foreign matter rearwardly along the screen 31 to the chute 20. That is to say, by rotating the shaft 43 in the direction of the arrow 76, as shown in Fig. 4, the eccentrics 44 will vibrate 5 the screen 31 by moving the same upwardly and rearwardly thereby throwing the foreign matter toward the chute 20 in step by step movements.

The shaft 52 must rotate in a clockwise direction as indicated by the arrow 77 on Fig. 4 so as 10 to engage the material and transfer it by impact along the upwardly and rearwardly inclined discharge passageway which has a closed top and an open bottom.

The mixture of used sand and foreign matter 15 which is shoveled into the hopper 19, is prevented by the rear wall 78 thereof from going beyond a position back of a vertical plane extending through the rear portion of the housing 46. It is preferred that the screened material fall on 20 to the housing 46 and the inclined walls of the hopper 30 including the laterally inclined walls 30' shown in Fig. 4. The screened material will thus be compelled to slide from the walls of the hopper into the opening in the bottom thereof 25 and consequently the distance which the screened material falls by gravity will be shortened and its descending velocity decreased. The discharge passageway 22 is in the form of an inverted U-shaped frame or chute detachably bolted at 79 30 and 80 to the main frame 8. The rotor comprising the spiders 54, 54 and the flights 59, 60, is mounted at the rear end portion of the passageway 22 intermediate the ends of the frame 8 and adjacent to and below the opening 81 through 35 which material is received from the hopper 30. An auxiliary hopper 82 may be mounted on the inverted chute 22, as shown in Fig. 4, not only to direct the screened material into the upper side of the cylindrical path of the flights 59 and 40 60 but also to intercept the gravity fall of some 45 of the material, thereby decreasing its velocity and assuring its being acted upon by the impact of the flights 59 and 60, when in the dotted line position shown in Fig. 4. The rotation of the shaft 52 in a clockwise direction as viewed in Fig. 4 should be at such speed as to assure the impacting of substantially all of the material by the flights 59 and 60. However, it is preferred to have the discharge passageway provided with an 50 open bottom so that such material as is not discharged from the rear end of the machine, may fall on to the floor under the frame 8.

Inasmuch as Fig. 5 is a section taken on the line 5—5 of Fig. 1, looking rearwardly, the trailing face of the flight 59 is viewed in Fig. 5, and in Fig. 6 is shown to be V-shaped. The leading face 83 is also V-shaped. When the rotor operates in a clockwise direction as viewed in Fig. 4, the leading face 83 of Fig. 6 moves in the direction of the arrow 84. Since the leading face 83 of each of the flights 59 and 60 is receding as shown in Fig. 6, or V-shaped when viewed in plan while in its top position, the screened material will receive such impacts as not only to aerate 65 the same but also thoroughly to mix the same during its discharge from the rear end of the machine. That is to say, since the impact faces of the flights are in intersecting planes, the material will be thrown along intersecting paths 70 diagonally across the inverted U-shaped chute from opposite sides, thereby thoroughly mixing or blending the screened sand into a homogeneous mixture by the time it reaches the pile of screened and aerated sand back of the machine and dis- 75

tant therefrom. That is to say, not only is the impacted material thrown through the atmosphere in planes extending tangentially from the upper side of the cylindrical path of the flights 5 for the purpose of securing aeration, but the material is also thrown along intersecting paths for securing thorough mixing and blending.

Reverting to the hopper structure shown in Figs. 4 and 5, it will be seen that the walls 30', 10 30' may be supported at their lower portions on the housing 46 abutments 85, 85 made integral with the housing 46; these abutments may also serve as spacing and centering abutments for the lower portion of the walls 30', 30'.

15 Inasmuch as the foundry sand conditioning apparatus shown in the accompanying drawings is relatively small, it may be very readily pulled manually to any desired location in a foundry, and electric connection made at 86 to the motor 20 61 from any suitable electric power outlet in the foundry, and the motor may be started and stopped by means of the push-button switch 87, shown in Fig. 1. The screen 31 may be readily removed for cleaning or repair or for replacement by a screen of a different mesh. The flights 25 59 and 60 may be varied in number and each may be removed for repair or replacement. Although the portable conditioning apparatus is particularly adapted to the cleaning and blending of 30 foundry sand, it may have a general application and I therefore prefer to mount the inverted chute 22 for detachment from the frame 8 so that if desired it may be cleaned. In some instances, such as when light material in powdered 35 or desiccated form is to be aerated, the screen 31 may be entirely omitted or replaced by a relatively large mesh screen. It should also be noted that if the screen 31 is omitted and the granulated material will flow with sufficient freedom 40 from the bottom of the hopper 30, 30', the belt 64 may be replaced by one shorter in length and connected between the pulleys 63 and 66 only, so as to cut out the pulley 65. That is to say, when it is not necessary or desirable to vibrate 45 the supplemental frame relatively to the main frame, the pulley 65 may be disconnected from the motor so that only the pulley 66 will be driven in a clockwise direction, as viewed in Fig. 4. However, as above explained, when the machine 50 is to be used in foundries for reconditioning used foundry sand, I prefer to combine the separating mechanism with the rotor and rely on the latter for its fan action and impact action to aerate the screened sand and thoroughly mix or blend 55 the same for re-use in future foundry work.

The opening at the rear lower edge of the hopper 19 may be regulated by means of the vertical gate in the form of a baffle plate 88 which may be secured in adjusted position at adjusted elevation by means of bolts, as shown in Fig. 4.

Obviously those skilled in the art may make various changes in the details and arrangement of parts without departing from the spirit and scope of the invention as defined by the claims 65 hereto appended, and I therefore wish not to be restricted to the precise construction herein disclosed.

Having thus described and shown an embodiment of my invention, what I desire to secure 70 by Letters Patent of the United States is:

1. In apparatus for conditioning granular material, the combination with a main frame, of an auxiliary frame, a plurality of spaced-apart coil springs for mounting said auxiliary frame on said main frame, a screen on the auxiliary frame to move bodily therewith, a hopper on said auxiliary frame under said screen, mechanism comprising a horizontal transverse shaft for vibrating said auxiliary frame together with said screen in orbital paths to effect conveying of unscreened material over said screen from the front feed end toward the rear end thereof and the depositing of screened material into said hopper, a rotary impeller mounted on the underside of said main frame and comprising a horizontal transverse shaft parallel to said first-named shaft, a motor on said main frame, driving connections between said motor and both of said horizontal shafts to rotate the latter in unison, mechanism for journaling the impeller shaft in said main frame so as to occupy such position under said hopper as to receive screened material falling by gravity from outside the periphery for impact tangentially of the peripheral path of the impeller to throw the material from the top side 25 of the impeller rearwardly from under the main frame and the machine to a position distant therefrom.

2. In a portable machine for conditioning granular material, the combination with a vehicle 30 comprising a frame with one end supported on a steering wheel unit and the other end on spaced-apart wheels, of a supplemental frame, a plurality of springs for supporting said supplemental frame on said main frame, a rotary aerator 35 mounted at the lower portion of said main frame for rotation relatively thereto on a horizontal transverse axis, mechanism comprising a transverse shaft on said supplemental frame for imparting to the latter a gyratory vibration, a 40 screen on said supplemental frame, means for guiding screened material to said rotary aerator, a motor on said main frame, means for driving said shafts in unison from said motor, an inverted open bottomed U-shaped discharge chute 45 leading from said aerator outwardly from the vehicle frame, and means for driving said aerator with its top rotating toward the rear outer open end of said chute.

3. In apparatus for conditioning granular material, the combination with a vehicle comprising a wheel supported main frame, of a supplemental frame, a plurality of upright coil springs mounted on said main frame, mechanism on the main frame extending into said springs to prevent the latter from moving laterally, means comprising inverted cups with cylinders in their bottoms extending into the tops of said springs to limit the lateral movement of said supplemental frame, a shaft journaled in said supplemental frame and 60 having eccentric mechanism for effecting gyratory vibration relative to said main frame as permitted by said springs, a screen on said supplemental frame having a material receiving end at the front of said vehicle, a rotor aerator, 65 means for guiding screened material to said rotor aerator, and an inverted open bottomed chute leading from said aerator to guide material rearwardly from the rear end of the machine.

FRED B. HENRY. 70
